UNITED STATES PATENT OFFICE

ALBERT S. HOWELL, OF CHICAGO, ILLINOIS, ASSIGNOR TO THE BELL & HOWELL COMPANY, OF CHICAGO, ILLINOIS, A CORPORATION OF ILLINOIS

PHOTOGRAPHIC PRINTING MACHINE

Application filed April 2, 1928. Serial No. 286,659.

My invention relates particularly to machines for printing motion picture film although not limited to this use alone. The invention contemplates, in the main, a photographic printing machine involving means whereby a plurality of longitudinal sections of a photographically sensitized strip, such as an unexposed positive motion picture film, may be exposed to or printed 10 from different photographic printing or negative strips, so that a plurality of subjects, preferably related, and particularly related visual sound and motion picture records, may be printed on the positive or sensitized strip, 15 and the main object of the invention resides in the provision of such a machine which is adjustable to vary the relation of the portions of the sensitized or positive strip upon which are printed the several subjects, with a view 20 toward the provision of such a machine which is adjustable to vary the lateral relation of the portions of the sensitized or positive strip upon which are printed the several subjects, whereby to provide a machine of the above 25 character which is adapted to meet a variety of conditions or requirements, and further with a view toward convenience, high production, and quality, particularly in the production of a single projection or record medium 30 bearing related visual sound records and motion pictures for use in the exhibiting of the so-called talking motion pictures.

With this object in view my invention consists in certain features of novelty in the construction, combination, and arrangement of parts by which the said object and certain other objects, hereinafter appearing are effected, all as fully described with reference to the accompanying drawings and more particularly pointed out in the appended claims.

In the said drawings—

Figure 1 is a front elevation of a motion picture film printing machine embodying my invention;

Figure 2 is an enlarged partial section on the line 2—2 of Figure 1;

Figure 3 is an enlarged front elevation of one of the exposing devices of the machine 50 with parts broken away and in section;

Figure 4 is a section on the line 4—4 of Figure 3;

Figure 5 is an enlarged front elevation of the image forming lens carrying structure of the machine, hereinafter described, with parts 55 removed, broken away and in section;

Figure 6 is a perspective view of a portion of one of the exposure devices of the machine;

Figure 7 is a perspective view of the prism 60 and shutter carrying member of one of the exposure devices of the machine;

Figure 8 is a bottom plan view of this prism and shutter carrying block;

Figure 9 is a top plan view of one of the 65 exposure devices of the machine;

Figures 10, 11, and 12 are face views of the interchangeable aperture plates of one of the exposure devices of the machine;

Figure 13 is a diagrammatic view showing 70 the paths of the several film strips on the machine;

Figures 14, 15, and 16 are partial face views of positive strips printed on the machine in respective of several adjustments 75 thereof.

Like characters of reference indicate like parts in the several views.

Referring to the drawings, 1 designates a pedestal which supports the machine, and 80 mounted at the top of this pedestal is a composite frame 2 which carries the mechanism of the machine. See Figure 1. Arranged at the top of the frame 2 is one exposure device which will now be described, briefly 85 in many respects inasmuch as the same is similar in many details to the one fully described and claimed in my co-pending application for U. S. Letters Patent, Serial No. 200,163, filed June 20, 1927, for improvement in photographic printing machine.

An upper portion of the frame 2 forms a light tight vertical lamp chamber 3 wherein is mounted an incandescent electric lamp 4 of suitable design which provides the 95 printing light for the above referred to exposure device. See Figures 1 and 2.

Arranged on the frame 2 immediately to the rear of the lamp chamber 3 is a motor casing 5 and mounted within this casing 100

with its shaft extending in parallelism with the focal axis, is an electric motor 6 for driving the machine.

The filament of the lamp 4 is centered with the focal axis of the above referred to exposure device, and the lamp chamber 3 is provided with a light opening, also alined with said focal axis, across which is disposed a light diffusing element in the form of a ground glass 7. See Figure 2. The frame 2 has a vertical transverse wall 8, in front of the light opening of the lamp chamber, which is apertured at said focal axis, and an optical condenser 9 is disposed in this opening in alinement with said focal axis for cooperation with the lamp 4 and ground glass 7 to effect a printing light.

A second frame 11 is mounted on the frame 2 for vertical adjustment and this adjustment is controlled by a manually controlled mechanism generally indicated at 11 in Figure 1. The frame 11 forms a transverse wall immediately in front of wall 8 of the frame 2, and is apertured on the said focal axis, and carried with the frame 11 immediately in front of the transverse wall thereof is a vertically extending intermittent negative film feed guide 12 provided with a light aperture corresponding with the said focal axis.

Intermittent film feeding mechanism, generally indicated at 13 in Figure 2, carried on the frame 2 is provided for intermittently feeding a negative motion picture bearing film strip 14 in the guide 12. This feeding mechanism is inclusive of a cam shaft 15 which is disposed in parallelism with said focal axis and is driven from the motor 6 through gearing and clutch mechanism generally indicated at 16. Vertical adjustment of the frame 11 with respect to the frame 2 effects the "framing" of the negative film 14 because the guide 12 is carried on the frame 11 while the feeding mechanism 13 is carried on the frame 2.

The frame 11 is provided with a support rail 17 which is disposed in parallelism with the said focal axis, and mounted on this rail for independent adjustment therealong are two supports 18 and 19. See Figure 1. Mounted on the outer support 18 is a frame 21 which is inclusive of a chamber 22 corresponding with the above noted focal axis. See Figures 1 and 2. The rear end of this chamber is formed by a vertically extending intermittent positive film feed guide 23 provided with a light aperture corresponding with the said focal axis.

Intermittent film feeding mechanism, generally indicated at 24 in Figure 2, carried on the frame 21 is provided for intermittently feeding an unexposed positive motion picture film strip 25 in the guide 23. This feeding mechanism is inclusive of a cam shaft 26 which is disposed in parallelism with the

aforementioned focal axis and is driven from and in timed relation with the hereinbefore mentioned cam shaft 15 by means of drive shaft means 27 partially shown in Figure 2, this drive shaft means involving usual slip joint means whereby the frame 21 may be adjusted along the rail 17 for purposes herein-after described.

A revolving segmental light shutter 28 is secured on the cam shaft 26 and sweeps over the exposure aperture of the guide 23 to intermittently interrupt exposure of the positive film 25 during intermittent movement thereof in the guide 23 effected by rotation of the cam shaft 26 forming a part of the intermittent feeding mechanism 24, the intermittent feeding mechanism 13 being timed with the feeding mechanism 24 to move the negative film 14 in the guide 12 while the shutter 28 interrupts exposure of the positive film 25 in the guide 23.

The hereinbefore mentioned support 19, which is adjustable along the support rail 17 of the frame 11 and longitudinally of the hereinbefore mentioned focal axis, is provided at its upper end with a tubular formation 31 which is disposed correspondingly with the said focal axis and extends therefrom in the direction of the frame 21 and telescopically extends into the chamber 22 with its extended end for longitudinal movement with respect thereto. See Figure 1. Mounted on the support member 19, at the other end of the tubular formation 31, for vertical movement with respect thereto normal to the said focal axis, by means of spaced opposing slide bearings 32 disposed on opposite sides of this tubular formation, is a support or bearing member 33 provided with a bore 34 therethrough surrounding the said focal axis. See Figures 1 and 5. The support member 33 is adjusted with respect to the support member 19 along the slide bearings 32 by a screw adjustment means generally indicated at 35 in Figure 5.

Mounted on the support member 33, on the side thereof facing the projection device, for horizontal movement with respect thereto normal to the said focal axis and normal to the adjusting movement of this support member, by means of spaced opposing slide bearings 36 disposed on opposite sides of the said focal axis, is a support member 37 provided with a bore 38 therethrough surrounding the said focal axis. See Figures 1 and 5. The support member 37 is provided with an indicating dial flange 39 disposed normal to the said focal axis and facing forwardly, and the support member 37 is adjusted with respect to the support member 33 along the side bearings 36 by a screw adjustment means including a screw 41 screwthreaded through the dial flange 39 in parallelism with the slide bearings 36.

Secured on the side of the support mem-

ber 37 facing the projection device is a tubular member 42 forming a portion of this support member and disposed coaxially with the bore 38 thereof. See Figures 1 and 5. 5 Screwthreaded into the bore 38 of the support member 38 and projecting therefrom in the bore of the tubular member 42 is an image forming or photographic lens 43 of a usual type provided with an adjustable iris mechanism which is inclusive of an external ring 44 angularly movable with respect to the body of the lens for adjusting the iris mechanism. 10

Adjustment of the ring 44 is controlled 15 from the exterior of the support member 37 and the tubular member 42 by an exterior knob 45 secured on the outer end of a revolute shaft 46 disposed coaxially with the dial flange and operatively connected with the 20 ring 44 by means of bevel gearing 47. A dial 48 secured on the shaft 46 is disposed on the outside of the dial flange 39 and cooperates with a stationary pointer 49 secured on the dial flange to indicate adjustment of the iris 25 mechanism of the lens 43.

A telescopic tubular structure 51 surrounds the said focal axis and extends between the projection or negative film guide 12 and the tubular member 42, thus completing the enclosure 30 of the printing light path between the negative guide 12 and the positive guide 23, this tubular structure 51 being provided with a side opening formation 52 across which is disposed a ruby glass 53 for the inspection of the negative film at the aperture of the guide 12. In addition the tubular light enclosing formation between the guides 12 and 23 is extended to the rear of the guide 23, as designated at 54, across which 40 is disposed a ruby glass 55 for the inspection of the image on the positive film at the aperture of the guide 23.

The above described exposure device is of the space printing type and is adapted for reduction printing in order to print the standard width picture of the standard width negative film 14 upon a section of lesser width of the standard width positive film 25, thus leaving another longitudinal section of the 50 positive film unprinted for the printing thereon of another subject, such as a visual sound record related to the motion picture. In order that the section of the film not printed in this exposure device is not exposed therein, the exposure aperture of the positive film guide 13 is reduced to conform to the size of the picture printed on the positive film from the negative film 14.

In order that the above exposure device 60 be adjustable to vary the position and size of the picture printed on the positive film 25 from the negative film 14 the exposure apertured face guide plate of the guide 23 is interchangeable, in a manner unnecessary to be 65 described, to effect the desired exposure aper-

ture in this guide. Figures 10, 11 and 12 show interchangeable exposure aperture plates 56 for the guide 23. The plate shown in Figure 10 has a reduced exposure aperture 57 disposed at one side, and the plate shown in Figure 12 has an exposure aperture 58 of the same size disposed at the correspondingly opposite side. The plate shown in Figure 11 has a further reduced exposure aperture 59 centrally disposed.

The use of the plate shown in Figure 10 provides for the printing of the motion picture on the positive film as shown at 61 in Figure 14, while the use of the plate shown in Figure 12 provides for the printing of the motion picture on the positive film as shown at 62 in Figure 15, and the use of the plate shown in Figure 11 provides for the printing of the motion picture on the positive film as shown at 63 in Figure 16.

In adjusting the above described exposure device in correspondence with the use of a desired aperture plate, the support members 18 and 19, carrying the lens 43 and the positive exposure guide 23, are adjusted along the support rail 17 to adjustably position the lens 43 and the guide 23 to effect the proper picture size and lens focus, and the support 37 is adjusted laterally along the slide bearings 36 to adjustably position the lens transversely to effect the proper transverse disposition of the projected picture to correspond with the exposure aperture of the guide 23.

In order that an additional record, such as a visual sound record preferably related with the motion picture printed upon the positive film 25, may be printed upon the longitudinal section of the positive film not exposed by the aforementioned exposure device, an additional exposure device is provided, which 100 will now be described.

Disposed at a lower point on the frame 2 and to one side of the pedestal 1 is a revolute horizontal shaft 64 which projects forwardly from the frame 2. See Figures 1, 3 and 4. Formed on this shaft immediately forward of the frame 2 is a peripherally toothed wheel 65. The shaft 64 projects forwardly of the wheel 65, and secured on the forwardly projecting end of this shaft is a second peripherally toothed wheel 66 forming with the wheel 65 and the portion of the shaft 64 between these wheels a film sprocket. This sprocket constitutes a constant feed sprocket and is driven from the cam shaft 26 in timed 110 relation therewith through a gear and shaft driving train 67 which is inclusive of a gear 68 secured on the shaft 64 within an enclosure of the frame 2. See Figures 2, 3, 4 and 9.

The wheels 65 and 66 have peripheral flanges 69 extending toward each other, thus forming undercuts on the inner sides thereof, and a stationary closed passage structure 71 is disposed between these wheels and has a generally circular form to correspond with 120 125

the wheels, the peripheral edges of this structure being shouldered, as designated at 72 to correspond with the flanges 69 of the wheels. See Figures 3, 4 and 6.

5 The lower portion of the closed passage structure 71 is provided with an extension 73 projecting downwardly between the flanges 69 of the wheels 65 and 66 and this extension forms, outwardly beyond these 10 wheels, a lamp chamber 74 in cooperation with a chambered forward extension 75 of the frame 2 to which the extension 73 is secured to fix the structure 71. Mounted within the chamber 74 by means of a suitable 15 socket 76 is an incandescent electric lamp 77 which provides a printing light.

Formed in the structure 71 and extending upwardly from the chamber 74 and between the wheels 65 and 66 is a light passage 78 20 which is disposed to one side of the vertical plane of the shaft 64. This passage leads upwardly to a horizontal slide opening 79 in the structure 71 which extends from the side of this structure inwardly beyond the 25 shaft 64, the slide opening being disposed partially above this shaft.

A slide block 81 is engaged in the slide opening 79 for removal therefrom, this block being releasably held in position in the slide 30 opening by a latch spring 82. See Figures 3, 4, and 7. The slide block 81 overlies the light passage 78 and is provided with a pair of diagonally disposed and transversely 35 spaced light passages 83 therethrough and separated by a partition 84 and extending upwardly from the light passage 78 to points overlying the shaft 64. Another pair of transversely spaced light passages 85 in the structure 71 and separated by a partition 86 40 extend upwardly from the upper ends of respective of the passages 83 to the upper surface of the structure 71 which is disposed on a horizontal chord of the wheels 65 and 66.

Secured on the slide block 81 and disposed 45 in respective of the light passages 83 is a pair of glass reflecting prisms 87 of parallelogram form which reflect printing light, transmitted thereto from the lamp 77 through the light passage 78, upwardly through respective of the light passages 85, it being observed 50 that the intermediate angling of the light passages avoids the shaft 64 and that completion of the angled portion of the passages by the removable slide block 81 on which are 55 mounted the reflecting prisms 87 provides a desirable structure affording access to the prisms.

Mounted on suitable slide bearings 88 at 60 respective sides of the lower surface of the slide block 81 are two shutters 89 which are movable independently in said slide bearings into and out of position across the respective light passages 83 to cut off the printing light thereto for purposes hereinafter described. 65 See Figures 7 and 8. These shutters are

manipulated when the slide block 81 is removed from the slide opening 79.

Secured on the aforementioned upper horizontal surface of the structure 71 is an inner film face guide member 91. See Figures 70 3, 4 and 6. The intermediate portion of the upper or film guiding face thereof is curved correspondingly with the peripheries of the wheels 65 and 66 while the end portions of this guiding face extend tangentially with 75 respect to said intermediate curved portion. Another film face guide member 92 is pivoted to the frame 2, as designated at 93, for movement into and out of position overlying the face guide member 91, the guide member 92 being releasably held in said position by a spring device 94 cooperating with an adjustable stop device 95 between the frame 2 and this guide member. See Figures 3, 4 and 9. 80

When the guide member 92 is so positioned it forms with the guide members 91 a film guide disposed for guiding superposed films engaged on the sprocket including the wheels 65 and 66. Accordingly the lower face of the 90 guide member 92 is shaped correspondingly with the upper face of the guide member 91, and the guide member 92 includes a movable block 96 forming the intermediate portion of the guide surface and upon which an adjustable spring pressure device, generally indicated at 97, acts to effect a desired pressure 95 on the film in the guide. 100

The guide member 91 is narrower than the space between the flanges 69 of the wheels 65 and 66 and is equally spaced therefrom, so that printing light projected upwardly through the light passages 85 of the structure 71 plays on the portions of the film in the guide, comprising the guide members 91 and 92, between the guide member 91 and the flanges 69 for printing these portions of a positive film overlying a negative film in this guide. When it is desired to expose but one of these sections of the films in this guide 110 one of the shutters 89 is closed to cut off the printing light from its respective light passage 85 and space between the flange 69 of the corresponding sprocket wheel 65 or 66. 105

Thus are provided two transversely arranged or spaced exposure apertures in the guide comprising the guide members 91 and 92, and in order that the printing light thereat may be varied the following is provided. 115 See Figures 3, 4 and 6.

Pairs of arcuate shutter members 101 are disposed between the guide member 91 and the wheels 65 and 66, and each pair is arranged on opposite sides of the respective light passage 85 of the structure 71, and these shutter members are movable longitudinally of the guide, comprising the guide members 91 and 92, and corresponding with the periphery of the wheels 65 or 66 to vary 125 the corresponding exposure opening of the 130

guide. These shutter members 101 have the outer arcuate surfaces thereof shouldered, as designated at 102, to correspond with the undercut of the wheels 65 and 66 provided by the flanges 69 thereof, and are adjustably positioned in the said movement thereof by means of headed screws 103 engaged in shouldered slots 104, through the shutter members 101, and screwthreaded into the guide member 91.

The exposure device including the guide comprising the guide members 91 and 92 is adapted to print the longitudinal section or sections of the positive film 25 not printed in the exposure guide including the guides 12 and 23 from a second standard negative film strip 105 which preferably bears a visual sound record or records. Thus, where one subject such as the motion picture is printed upon the section 61 of the positive film, see Figure 14, the other subject or sound record is printed upon the section 106 of the positive film, the proper shutter 89 being closed to prevent double exposure of the corresponding section of the positive film.

Where one subject such as the motion picture is printed upon the section 62 of the positive film, see Figure 15, the other subject or sound record is printed upon the section 107 of the positive film, the proper shutter 89 being closed to prevent double exposure of the corresponding section of the positive film.

Where one subject such as the motion picture is printed upon the section 63 of the positive film, see Figure 16, the other subject or subjects, such as a sound record or records, is or are printed upon the sections 108 of the positive film, both of the shutters 89 being open in this case.

Thus are provided two devices for exposing different longitudinal sections of the positive film 25 in printing relation respectively with the negative films 14 and 105 progressively therewith, each of said exposure devices being adapted to prevent exposure thereby of the portion of the positive film printed by the other, the feeding devices being driven in timed relation from the motor 6 for the progressive printing along the positive film simultaneously by the negative films 14 and 105.

The films are carried and fed to and from the hereinabove mentioned exposure guides in the following manner. See Figures 1 and 13.

The negative film 14 is fed from a feed spool 111 to an upper constant feed sprocket 112, thence through a compensating loop to the upper end of the guide 12 in which it is fed downwardly by the intermittent feed mechanism 13, thence from the lower end of this guide through a compensating loop to a lower constant feed sprocket 113, and finally to a take up spool 114.

The positive film 25 is fed from a feed

spool 115 to a constant feed sprocket 116, thence through the exposure guide, comprising the guide members 91 and 92, through which it is fed by the constant feed sprocket including the wheels 65 and 66, thence to a constant feed sprocket 117, thence through a compensating loop to the lower end of the guide 23 in which it is fed upwardly by the intermittent feed mechanism 24, thence from the upper end of this guide 23 through a compensating loop to a constant feed sprocket 118, and finally to a take up spool 119.

The negative film 105 is fed from a feed spool 121 to the constant feed sprocket 116, thence through the exposure guide, comprising the guide members 91 and 92, through which it is fed in printing relation with the positive film 25 by the constant feed sprocket including the wheels 65 and 66, thence to a constant feed sprocket 122, and finally to a take up spool 123.

The constant feed sprockets 112, 113, 116, 117, 118 and 122 are all driven from the motor 6 in timed relation with the intermittent feeding mechanisms 13 and 24 and the constant feed sprocket comprising the wheels 65 and 66 by suitable driving mechanism unnecessary to be described, and the take up spools 114, 119 and 123 are driven from the motor 6 by mechanism which is inclusive of belts 124 which accommodate for the varying diameter of the rolls of film on the several take up spools.

It is to be observed that as shown the film for which the machine is adapted is standard motion picture film and that the motion picture printed thereon is comparatively wide as compared with the width of the sound record printed thereon. It will be further observed that the aforementioned space printing device which prints the motion picture is adaptable for printing a full size motion picture on the positive film, in which case the sound record printing device is not used.

While I have herein shown and particularly described the preferred embodiment of my invention I do not wish to be limited to the precise details of construction shown as changes may readily be made without departing from the spirit of my invention, but having thus described my invention, I claim as new and desire to secure by Letters Patent the following:

1. In a photographic printing machine the combination with a revoluble film feed sprocket comprising two axially spaced wheels and an axial shaft extending therebetween, of a film guide disposed for guiding superposed films engaged on said sprocket and provided with an exposure aperture between said wheels and facing inwardly of the sprocket, closed light passage means between said wheels and leading to said exposure

aperture and angled to avoid said shaft and including a removable structure completing the angled portion thereof, and reflecting means carried on said removable structure 5 for reflecting printing light through said passage means to said exposure aperture.

2. In a photographic printing machine the combination with a revoluble film feed sprocket comprising two axially spaced 10 wheels and an axial shaft extending therebetween, of a film guide disposed for guiding superposed films engaged on said sprocket and provided with an exposure aperture between said wheels and facing radially inwardly of the sprocket, closed light passage means between said wheels and leading to 15 said exposure aperture from the opposite side of said sprocket and intermediately angled to avoid said shaft and including a removable structure completing the angled portion thereof, and a single glass reflecting 20 prism of parallelogram form mounted on said removable structure for reflecting printing light through said passage means to said 25 exposure aperture.

3. In a photographic printing machine the combination with a revoluble film feed sprocket comprising two axially spaced wheels and an axial shaft extending there- 30 between, of a film guide disposed for guiding superposed films engaged on said sprocket and provided with two transversely arranged exposure apertures between said wheels and facing inwardly of the sprocket, closed pas- 35 sage means providing two independent closed passages between said wheels and leading to respective of said exposure apertures and angled to avoid said shaft, reflecting means within said closed passages for reflecting 40 printing light to said exposure apertures, and means for selectively cutting off printing light to said exposure apertures.

4. In a photographic printing machine the combination with a revoluble film feed 45 sprocket comprising two axially spaced wheels and an axial shaft extending therebetween, of a film guide disposed for guiding superposed films engaged on said sprocket and provided with two transversely spaced 50 exposure apertures between said wheels and facing inwardly of the sprocket, closed pas- 55 sage means providing two independent closed passages between said wheels and leading to respective of said exposure apertures and angled to avoid said shaft and including a removable structure completing the angled portion thereof, reflecting means carried on 60 said removable structure for reflecting printing light through said passage means to re- 65 spective of said exposure apertures, and shutter means carried on said removable structure for selectively cutting off the printing light to said exposure openings.

5. In a photographic printing machine the 65 combination with a revoluble film feed

sprocket comprising two axially spaced wheels and an axial shaft extending therebetween, of a film guide disposed for guiding superposed films engaged on said sprocket and provided with two transversely spaced 70 exposure apertures between said wheels and facing inwardly of the sprocket, closed pas- 75 sage means providing two independent closed passages between said wheels and leading to respective of said exposure apertures and intermediately angled to avoid said shaft and including a removable structure completing the angled portion thereof, a pair of glass reflecting prisms of parallelogram form mounted on said removable structure for reflecting printing light through respective of said 80 exposure apertures to said exposure apertures and a pair of independently movable shutters carried on said removable structure for cutting off the printing light to respective of said 85 exposure apertures.

6. In a photographic printing machine the combination with a revoluble feed sprocket wheel, of a film guide associated therewith including an inner face guide member spaced 90 axially from said wheel to form an exposure opening, an arcuate shutter member disposed correspondingly with the periphery of said sprocket wheel and between the same and said guide member and movable correspondingly 95 to vary said exposure opening, and means for securing said shutter member with said guide member and adapted to permit said adjustment of said shutter member.

7. In a photographic printing machine the combination with a revoluble feed sprocket wheel undercut on one side, of a film guide associated therewith including an inner face guide member disposed on said side of the sprocket wheel and spaced axially therefrom 100 to form an exposure opening, an arcuate shutter member disposed correspondingly with the periphery of said sprocket wheel and between the same and said guide member and having the outer surface thereof shouldered to correspond with the undercut of the wheel, and headed screws engaged in shouldered slots through said shutter member and screw-threaded into said guide member whereby 105 said shutter member is adjustable corresponding with the periphery of said wheel to vary said exposure opening.

8. In a photographic printing machine the combination with a revoluble film feed sprocket including two axially spaced wheels, of a film guide disposed for guiding superposed films engaged on said sprocket and including an inner face guide member disposed between and spaced from said wheels to form 110 exposure openings, shutter members between said guide member and respective sprockets and movable longitudinally of said guide for varying said exposure openings and means for adjustably positioning said shutter members in their said movement.

9. In a photographic printing machine the combination with a revoluble film feed sprocket including two axially spaced wheels, of a film guide disposed for guide superposed films engaged on said sprocket and including an inner face guide member disposed between and spaced from said wheels to form exposure openings, arcuate shutter members disposed correspondingly with the periphery of said sprocket and between said guide member and respective sprockets and movable longitudinally of said guide for varying said exposure openings, and means for adjustably securing said shutter members on said face guide member in this said movement.

10. In a photographic printing machine the combination with a revoluble film feed sprocket including two axially spaced wheels having peripheral flanges extending toward each other, of a film guide disposed for guiding superposed films engaged on said sprocket and including an inner face guide member disposed between and spaced from said wheels to form exposure openings, arcuate shutter members disposed correspondingly with the periphery of said sprocket and between said guide member and respective sprockets and underlying said flanges and having the corresponding surfaces thereof stepped to accommodate said flanges, and headed screws passing through shouldered slots in said shutter members and screw-threaded into the sides of said face guide member for adjustably securing said shutter members longitudinally of said guide and about the axis of said sprocket.

In witness whereof I hereunto affix my signature this 29th day of March, 1928.

ALBERT S. HOWELL.
